UNITED STATES PATENT OFFICE.

CHARLES MEGOW, OF SAN FRANCISCO, CALIFORNIA, ASSIGNOR OF ONE-HALF TO JOHN L. ANDERSON, OF SAME PLACE.

ADJUSTABLE WINDOW-SASH.

SPECIFICATION forming part of Letters Patent No. 416,004, dated November 26, 1889.

Application filed August 12, 1889. Serial No. 320,521. (No model.)

To all whom it may concern:

Be it known that I, CHARLES MEGOW, of the city and county of San Francisco, State of California, have invented an Improvement 5 in Adjustable Window-Sashes; and I hereby declare the following to be a full, clear, and exact description of the same.

My invention relates to that class of window-sashes which are pivoted at their sides, 10 whereby they are adapted to be reversed to permit ready and easy access to them from the inside for the purpose of washing them; and my invention relates particularly to that class of these pivotally-adjustable sashes in 15 which the inside and outside beads and the intervening parting-strips are themselves pivoted, so as to adapt them to be thrown backwardly in the window casing or frame, thereby freeing the sashes.

20 My invention consists in improved details of the construction, arrangement, and combination in this class of adjustable window-sashes, as will be hereinafter fully described, and specifically pointed out in the claims.

25 The object of my invention is to provide a simple and easily-operated window the sashes of which can be readily reversed to permit them to be reached.

Referring to the accompanying drawings 30 for a more complete explanation of my invention, Figure 1 is a perspective view of my adjustable window sashes and frame. Fig. 2 is a front elevation, the lower sash and the lower portion of the window-frame being in 35 section. Fig. 3 is a horizontal section on line *x x* of Fig. 2. Fig. 4 is a view of the sliding connecting-iron L.

A is the window frame or casing. B is the lower sash, and C is the upper sash. D is the 40 inside bead. E is the outside bead, and F is the parting-strip. These are all mounted in the sides of the window casing or frame in such a manner as will adapt them to be moved into and out of position, when in the former

45 position projecting inwardly and overlapping the stiles of the sashes, and in the latter position being withdrawn so as to free the sashes. These beads and parting-strip on each side are all pivoted upon cross-shafts G, 50 passing through the window-casing sides near the top thereof, and they are united at their

lower ends by means of a cross-plate H, from which a bar I—one on each side—extends inwardly into the sill of the window frame or casing in a suitable groove or seat a therein. 55 Now, by pushing outwardly these slide-bars the beads and parting-strips on each side are all moved outwardly together, turning about their hinged tops as centers and removing themselves from the stiles of the two sashes, 60 which in their normal position they confine to place, forming grooves in which they move. The slide-bars have hinged arms i, which are adapted to enter grooves a' in the window-sill to hold them in a position either out or in. 65

In the sides of the window frame or casing and opposite the stiles of each sash are made grooves J, which are faced by separated metal plates j on their outer surface, thus forming a kind of T-shaped channel. 70

In the stiles of each sash are made grooves K, commencing at about their centers and extending downwardly to the lower bar of each sash. These grooves are faced by separated plates k. 75

L are connecting-irons consisting of long bars, which are fitted and travel in the flanged grooves J of the window-casing sides and have shanked buttons or knobs l projecting from their centers and fitted in the 80 flanged grooves K of the sash-stiles. To the upper ends of the bars are connected the weight-cords M of the sashes. These bars are by means of the shanked knobs l connected with the sashes, and they form the 85 runners or guides by which the sashes move up and down, being confined to their seats by the metal flanges or plates j of the grooves J in which they run. The shanked knobs l, 90 which enter the grooves K of the sash-stiles, form pivots about which said sashes are turned in reversing them, and they also form guides which, traveling in the grooves K of the stiles, enable the sashes to be drawn down within reach after being turned. 95

The operation of the device is as follows: The sashes move up and down in the usual manner by means of the weights. They are held in normal position by means of the beads and parting-strips, which form the 100 grooves confining them. When it is desired to wash the glass of the sashes, the slide-bars

I in the sill of the casing are forced outwardly, thereby swinging the beads and parting-strips on each side backwardly on their pivotal centers above and freeing the window-sashes. 5 The lower sash is then turned about the shanked knobs *l* as centers and pulled down within reach, its grooves *K* traveling over said knobs. The upper sash is then likewise manipulated, whereby the outer side of the glass 10 of each sash may be easily reached.

I am aware that in adjustable sashes of this class the inside and outside beads and the intervening parting-strip have been made movable, so that they might be pushed back 15 out of the way, and thus free the window-sashes, and I do not claim such, broadly, but confine myself to the particular improved constructions described.

Having thus described my invention, what 20 I claim as new, and desire to secure by Letters Patent, is—

1. In combination with the sliding and swinging window-sashes, the movable and connected inside and outside beads and parting-strips on each side, and a pivotal shaft at 25 the top of said beads and strips, whereby they move outwardly about said shafts as centers, substantially as described.

2. In combination with the sliding and 30 swinging window-sashes, the movable inside and outside beads and parting-strips on each side, the pivotal shaft on which the upper ends of said beads and strips are mounted, the connecting-plate at the lower ends of said 35 beads and strips, and the slide-bars extending from said plate inwardly into a seat in the sill of the window-casing, substantially as described.

3. The window casing or frame having the 40 grooves *J* in its sides, with face-plates *j* and

the sashes of the window, in combination with the slide-bars *L*, mounted in the grooves of the window-casing and having shanked knobs *l*, extending therefrom and journaled in the stiles of the sashes, and the weighted 45 window-cords connected with the slide-bars, substantially as described.

4. The window casing or frame having grooves *J* in its sides, with face-plates *j*, the sashes having the grooves *K* in their stiles, 50 with face-plates *k*, in combination with the slide-bars *L*, mounted in the grooves of the window frame or casing and having the shanked knobs *l*, projecting therefrom and mounted in the grooves of the sash-stiles, 55 whereby said sashes may be reversed and moved on the knobs, and the weighted window-cords connected with the slide-bars, substantially as described.

5. The window frame or casing having the 60 grooves *J*, with face-plates *j* in its sides, and the sashes having grooves *K*, with face-plates *k* in their stiles, in combination with the slide-bars *L*, mounted in the grooves of the window frame or casing and having shanked 65 knobs *l*, mounted in the grooves of the sash-stiles, the weighted cords connected with the slide-bars, and the movable inside and outside beads and intervening parting-strips on 70 each side of the window frame or casing, pivoted at their tops and having a connecting-plate and slide-bar at their bases, substantially as described.

In witness whereof I have hereunto set my hand.

CHARLES MEGOW.
